UNITED STATES PATENT OFFICE.

ANNA M. WELSH, OF CINCINNATI, OHIO.

SAD-IRON HANDLE.

1,238,230.

Specification of Letters Patent. Patented Aug. 28, 1917.

Application filed November 20, 1916. Serial No. 132,252.

To all whom it may concern:

Be it known that I, ANNA M. WELSH, of Cincinnati, in the county of Hamilton and State of Ohio, have invented a certain new 5 and useful Improvement in Sad-Iron Handles, of which the following is a full, clear, and exact description, reference being had to the accompanying drawings, forming a part of this specification.

10 My invention relates to handles for sad irons.

The object of my invention is to provide in a handle for sad irons resilient members or standards whereby said handle may be 15 supported on a sad iron, thus providing a resilient medium or mounting between the handle and iron, thereby relieving to a great extent, the pressure and labor attendant upon the use of a sad iron.

20 In the drawings:

The figure is a side elevation of a sad iron provided with my new handle, one of the supports of said handle being shown in section.

25 The numeral 1 indicates the handle proper or gripping member for a sad iron. The said handle is arranged to be mounted on a plate 2 by supports 3. The plate 2 is provided with a latch 4 whereby it is adapted 30 to be secured to a sad iron 5 in the usual manner. It will be understood that my invention does not relate to the means of securing the plate 2 to the sad iron and, therefore, the latch 4 may be modified or other 35 means therefor substituted.

Secured to the upper side of the plate 2, near each end thereof, are bosses 6. On the under side of the handle 1, near the ends thereof, are bosses 7 of somewhat smaller 40 diameter than the bosses 6. Secured to the bosses 6 and 7 by means of rivets 8 or otherwise, are helical springs 9, whose coils are adapted to telescope as shown. The said

springs are constructed of steel straps of suitable width. While the helical springs 45 9 will ordinarily be of sufficient tensile and resilient efficiency to provide for the mounting of the handle 1, I have further shown in the drawings, arranged to coöperate with the helical springs 9, a spiral spring 10, 50 the said spiral spring being mounted on studs 11 provided on the bosses 6 and 7. The spiral springs 10 when provided, add to the resiliency of the mounting and therefore, increase the efficiency of the construction. 55

The nature and advantages of my invention will be apparent from the foregoing description to those skilled in the art to which the same appertains. When in use, the 60 spring supports 3 are, during the successive strokes, placed under compression, and the resiliency of the springs is thus caused at the end of each stroke to assist the operator in raising the arm for the return stroke. 65

Having thus described my invention, what I claim as new and desire to secure by Letters Patent is:-

1. In a handle for sad irons, the combination between a gripping member and a plate 70 adapted to be secured to a sad iron, of helical spring supports whereby said gripping member may be secured to said plate, the coils of said helical spring supports being arranged to telescope. 75

2. In a handle for sad irons, the combination between a gripping member and a plate adapted to be secured to a sad iron, of helical spring supports whereby said gripping member may be secured to said plate, 80 the coils of said helical spring supports being arranged to telescope, and spiral springs mounted within said helical springs between said gripping member and said support.

ANNA M. WELSH.
